UNITED STATES PATENT OFFICE.

LOUIS C. GANNY AND HARRY GOLDBERG, OF WILKES-BARRE, PENNSYLVANIA, AS
SIGNORS OF ONE-SIXTH TO THOMAS J. MAYOCK, ONE-SIXTH TO JAMES M. STACK,
BOTH OF WILKES-BARRE, PENNSYLVANIA, AND ONE-SIXTH TO MICHAEL MAYOCK,
OF MINERS MILLS, PENNSYLVANIA.

HOLDING DEVICE.

Application filed November 29, 1926. Serial No. 151,543.

This invention relates to a holding device for such articles as brooms, billiard-cues, brush handles, mop handles, telephones, dumb-bells, etc.

5 The primary object of this invention is the provision of a device which is simple in construction, effective in its function, and capable of being manufactured at small cost.

10 A further object of this invention is the provision of a device which comprises a light metallic, wooden, composition, or fiber frame structure capable of being quickly and securely fastened to a support of any kind.

15 A still further object of this invention is the provision of a device which comprises a thin metallic, wooden, composition, or fiber frame structure in which is mounted solid elastic holding or gripping members adapted to retain an article inserted therebetween.

20 Devices similar to that herein disclosed, have heretofore been proposed, but such devices, so far as we are aware, comprised holding or gripping members which were in the form of a hollow spherical member, or com-

25 prised members which were pressed into contact with the article to be retained, by means of springs. In the hollow spherical member, there does not seem to be sufficient pressure exerted against the article to effectively hold the same. In employing a device

30 in which the members are pressed into contact with the article by springs, such device necessitates a greater expenditure of time and money in the production of the same, be-

35 sides being liable, in the course of use, to become ineffective, due to gradual weakening and possibility of breaking of the spring. In the use of solid elastic members, upon insertion of an article therebetween, the ma-

40 terial of the members is caused to assume a configuration of the article, and due to the elasticity, tightly grip the same.

45 With the foregoing and other objects in view, our invention comprises certain novel combinations, constructions and arrangements of parts as will be hereinafter described, illustrated in the accompanying drawings, and more particularly pointed out in the appended claims.

50 In the drawings,

Fig. 1 is a plan view of one form of the invention.

Fig. 2 is a side elevation of the same.

Fig. 3 is a plan view of a slightly modified form of the invention. 55

Figs. 4 and 5 are perspective views disclosing two of the many applications of the invention.

Referring to the drawings by reference characters, A designates a thin metallic, 60 wooden, composition, or fiber frame structure, B designates solid elastic disk-like holding or gripping members. The frame structure A is stamped from thin sheet metal, or sheet-metal board, composition fiber or 65 wood, and comprises a back 1, and sides 2, each side 2 is of such configuration as to provide a pair of ears 3, and a substantially semi-circular article receiving depression 4. Each side 2, adjacent the ears 3, is stamped 70 out to provide securing lugs 5, which lugs lie in the plane of the back 1. Each side 2, in the bottom of the depression 4, is provided with an outwardly extending flange 6.

The ears 3 are apertured for the reception of pintles 7, each pintle mounting one of the before mentioned elastic members B. 75

Each elastic member B is composed of solid resilient substance such as rubber (preferably sponge rubber), and is in the 80 form of a disk of substantial width, but having the periphery thereof curved in the transverse direction thereof.

By referring to Figs. 1, 2 and 3, it will be noted that the gripping surface of each 85 member B is substantially spherical, and upon insertion of any article to be retained between the two adjacent gripping members, the material thereof will, in virtue of the elasticity of the members, expand about the 90 article, both in the lateral and circumferential direction of the members.

The frame structure being composed of thin sheet metal, wood, composition, or fiber, the edges thereof adjacent the bottoms of the 95 depressions 4, would be liable to mar or cut the article to be retained. To overcome this liability, the sides 2 adjacent the bottoms of the depressions are provided with the flanges 6. 100

While it is desirable to employ four securing lugs as shown in Figs. 1 and 2, the device may in some instances, be provided with only two lugs as shown in Fig. 3.

In the use of the device, the same is by 105 means of the lugs 5, secured to a wall or pro-

2
jection thereof, and, as shown in Figs. 4 and 5, the article has the substantially cylindrical portion thereof inserted between the two adjacent gripping members. Upon insertion 5 of the article, the opposite gripping members will both yield and rotate, causing the article to be drawn into the depressions 4, in contact with the flanges 6, and due to the great elasticity of the gripping members, 10 the article will be securely held in the device.

While we have shown and described certain embodiments of our invention, it is to be understood that we are not limited thereto, but reserve the right to make such changes 15 or alterations as fairly fall within the scope of the appended claims.

What we claim and desire to secure by Letters Patent is:

1. In a holding device, a thin frame structure comprising a bottom and sides at right angles thereto, each side being of such configuration as to provide a pair of ears and a depression therebetween, and having secur-

ing lugs adjacent each end thereof, said depression being provided with an outwardly 25 extending flange and gripping members supported by said ears.

2. In a holding device, a frame adapted to be secured to a wall, parallel pintles carried by the frame and having stationary axes, 30 and relatively thick rotatable solid disks mounted on said pintles and having parallel top and bottom flat faces through which the pintles pass, each of said disks being formed of elastic material and taking the shape of 35 a segment of a sphere, the pintles extending through the centers of the disks, said disks, due to their elasticity, being capable upon the insertion of an article between the same, of firmly expanding about said article and 40 securely holding the same in position.

In testimony whereof, we affix our signatures.

LOUIS C. GANNY.
HARRY GOLDBERG.
